J. W. BOND.

FLOATING SINKER.

APPLICATION FILED JULY 8, 1921.

1,408,927.

Patented Mar. 7, 1922.

UNITED STATES PATENT OFFICE.

JOHN WILLIAM BOND, OF VICTORIA, BRITISH COLUMBIA, CANADA.

FLOATING SINKER.

1,408,927.

Specification of Letters Patent.

Patented Mar. 7, 1922.

Application filed July 8, 1921. Serial No. 483,348.

To all whom it may concern:

Be it known that I, JOHN WILLIAM BOND, a subject of the King of Great Britain, and resident of the city of Victoria, in the Province of British Columbia and Dominion of Canada, have invented certain new and useful Improvements in Floating Sinkers, of which the following is a specification.

- This invention relates to improvements 10 in floating sinkers, and has for its objects to provide a sinker that will sink to a predetermined depth in the water and will rise on the surface as soon as a tension is applied against the same.
- 15 Further objects are to provide a floating sinker designed to be attached at one end to a boat and be fastened at the other end to the trolling spoon, or other device commonly used for the purpose.
- 20 These objects are attained by providing a device which consists of a shank extending through the centre of a disc having metal covered segments and which is adapted through suitable mechanism to assume a 25 horizontal position, or a vertical position when the same is designed to sink to a predetermined depth in the water.

Further objects still are to provide a device of simple construction and not liable 30 to go out of repair, and generally to adapt the several parts to perform the functions required of them.

It consists essentially of the improved construction hereinafter described in detail 35 in the accompanying specification and drawings.

In the drawings:

Figure 1 is a side elevation of the improved floating sinker.

40 Figure 2 is a fragmentary longitudinal section taken through part of the shank and sleeve.

Figure 3 is a sectional view taken through the centre of the disc.

45 Figure 4 is a perspective view of the resilient member designed to coact with the sleeve.

Figure 5 is a perspective view of the trigger.

50 Fig. 6 is a section on the shank showing the disc in rear elevation.

Referring to the drawings:

A designates the improved floating sinker comprising a shank 10 having a bent portion intermediate of the length thereof, as shown 55 at 11. This bent portion is provided with a small bearing 12 welded thereto and de-

signed to be engaged by a pin 13 extending transversely of the disc 14 mounted on the shank 10 and provided adjacent to the centre orifice 15 with two lugs 16 and 17 through which the pin 13 extends. The lug 17 may be provided with an additional orifice 18 through which the pin 13 may extend, in order to give an angular position to the disc 14.

The shank 10 is also provided with a collar 19 slidably mounted thereon and having a set screw 20, the end of which is designed to engage with one of a series of recesses 21 provided on the lower face of the shank 10 in order to secure the collar 19 thereon. Slidably mounted on the shank 10 is a sleeve 22 formed with two lugs 23 and 24 extending adjacent to each end of the sleeve 22 on the top face thereof. The sleeve 22 is also formed with a bridge 25 integral therewith and through which extends the resilient member 26 having an end curved downwardly and engaging the lug 23 while the end remote to the curved end bears against the lug 24 and has a bifurcated extension 27 curved upwardly, the purpose of which will be hereinafter made clear.

The sleeve 22 is provided at each end 85 thereof with pairs of apertured ears 28 and 29. The ears 29 carry a pin 30 on which is fulcrumed at 30' a trigger 31 formed with a lug 32 and provided with a transversely extending pin 33 against which the 90 bifurcated end 27 of the resilient member 26 is adapted to bear.

The trigger 31 is provided with a plurality of openings 34, one of which is engaged by a pin carried by a U-shaped member 35 95 to which is fastened a string or other flexible member 36 extending through an apertured lug 37 formed integral with an enlarged portion 38 formed on the end of the shank 10. The trigger 31 is also apertured adjacent to its fulcrum 30 at 39' and the said aperture is engaged by a pin carried by a U-shaped member 39 which carries fastened thereto the end of a string or other flexible member 40 which engages the roller 41 provided in an enlarged portion 38 of the shank 10 and extending along the shank 10, engaging the eyes 42 provided on the underface of the said shank.

The flexible member 40 engages the offset 110 apertured end 43 of the shank 10 and is looped at its outer end as shown at 44. The

apertured ears 28 provided on one end of the sleeve 22 are engaged by a pin pivotally engaging a lever 45 which is pivotally connected to the disc 14 as shown at 46. The 5 bridge 25 is provided with a set screw 47 which, when tightened, is adapted to bear against the resilient member 26 and forces the same downwardly across the lugs 23 and 24, thus forcing the bifurcated end 27 more 10 firmly against the pin 33 thereby holding the trigger 31 securely in the upward position.

The shank 10 is provided on the top thereof with a plurality of recesses 48 which are 15 designed to be engaged by the lug 32 provided on the trigger 31 when the same is rotated on its fulcrum to assume an upward position as shown in Figure 2 of the drawings. The collar 19, previously described 20 slidably, carried by the shank 10, may be formed with a guide member 49 which would be used for the same purpose as the guide member 42 designed to engage the flexible member 40 extending therethrough.

25 When this floating sinker is in use, the string or flexible member 40 is fastened through its looped end 44 to the rear end of the boat while the looped end 50 of the flexible member 36 is connected to the trolling spoon. The sleeve 22 is then moved along the shank 10 until the disc 14 connected thereto through the lever 45 will have assumed the desired inclination, when the trigger 31 will be raised, in order that 30 the lug 32 provided thereon may be caused to engage with one of the recesses 48 provided on the top of the shank 10.

It will be obvious that, when a certain 40 inclination of the disc has been tested and proved to give the desired results, the collar 19 may be adjusted on the shank 10 by means of the set screw 20. When the desired inclination of the disc 14 has been obtained, the sleeve 22 will merely have to be slid and brought to bear against the collar 19 when 45 the trigger 31 may be raised in position. The disc in this raised position, as shown in Figure 1, will sink to a predetermined depth in the water and will only be raised 50 when a fish will have caught the trolling spoon and will exert pull against the flexible member 36 which transmitting the pull to the upward end of the trigger 31, will cause the trigger 31 to pivot on its fulcrum 30, 55 thus causing the lug 32 to be disengaged from the recess 48, when the sleeve being free, will move to the outer end of the shank 10, thus bringing the disc 14 to approximately a horizontal position, when the same 60 will rise to the surface of the water and float thereon, thus proving the presence of a fish on the end of the troll.

It will also be obvious through the flexible member 40 engaging with the roller 41 and 65 extending along the shank 10 when the de-

vice is submitted to great water resistance or from increased tide currents or tide rips and boat speed, which, under ordinary circumstances, would result in parting of the line if no provision had been made to take 70 care of the abnormal strain. Further by means of the set screw 47, this may be adjusted, in order to adjust the degree of tension of the trigger 31. The disc 14 may be depressed and thrown out of action by 75 a quick pull being applied to the string 40.

When two of these sinkers are used, the pins 13 are caused to engage with the orifices 18 provided on the lug 16 of the disc so as to give an angular position to the said disc, 80 in order that the same may not always be one against the other but may be adapted to travel but at a predetermined distance from one another. The disc 14 may be reinforced 85 on the lower end thereof by means of a segmental metal sleeve 51 designed to fit over the lower end of the disc 14, as clearly shown in Figure 1 of the drawings.

The force necessary to throw the trigger 31 out of engagement may be varied also by 90 the adjustment of the U-shaped member 35 along the apertured shank thereof as it will be seen that, when the member 35 engages with one of the lower openings 34, a stronger pull will be necessary on the string 36 in 95 order to throw the trigger 31 down against the shank 10. When the device is increased in dimensions, the metal parts of the same will also have to be increased, particularly the shank 10, as the same is subjected to the 100 greatest strain.

As many changes could be made in the above construction, and many apparently widely different embodiments of my invention within the scope of the claims, constructed without departing from the spirit or scope thereof, it is intended that all matter contained in the accompanying specification and drawings shall be interpreted as 105 illustrative and not in a limiting sense. 110

What I claim as my invention is:

1. A floating sinker of the class described comprising a shank, a disc having an aperture in its centre and pivotally mounted on the shank, means slidably mounted on the shank designed to actuate the disc on its pivot, and means coacting with the last said means to secure the disc in a predetermined position. 115

2. A floating sinker of the class described comprising a shank, a disc having an aperture in its centre and pivotally mounted on the shank, a sleeve slidably mounted on the shank, means coacting with the sleeve to secure the disc on the shank in a predetermined position, and flexible members connected to the last said means as and for the purpose specified. 120

3. A floating sinker of the class described comprising a shank offset intermediate of 13

- the length thereof, a disc pivotally mounted on the offset of the shank, a sleeve slidably mounted on the shank, a connecting link between the sleeve and the disc, means pivotally mounted on the sleeve to secure the sleeve in a predetermined position, and flexible members connected to the said means designed to actuate the same.
4. A floating sinker of the class described comprising a shank offset intermediate of the length thereof, a disc pivotally mounted on the offset of the shank, a sleeve slidably mounted on the shank, a connecting link between the sleeve and the disc, a trigger pivotally mounted on the sleeve and provided with a plurality of orifices, resilient means coacting with the trigger, and flexible members connected to the trigger to disengage the same as and for the purpose specified.
5. The floating sinker claimed in claim 4, in which the shank is provided with a plurality of recesses, and a projection on the trigger designed to engage one of the recesses when the trigger assumes an upright position, as and for the purpose specified.
6. The floating sinker claimed in claim 4, in which the resilient means consists of a leaf spring having a bifurcated upwardly curved end designed to bear against pins provided on the trigger.
7. A floating sinker of the class described comprising a shank offset intermediate of the length thereof, a disc pivotally mounted on the offset of the shank, a sleeve slidably mounted on the shank and formed integral with a bridge member, a connecting link be-
- tween the sleeve and the disc, a trigger pivotally mounted on the sleeve and provided with a plurality of orifices, a leaf spring on the sleeve extending through the bridge and engaging the trigger, means on the bridge member to vary the pressure of the spring, the trigger being formed with a projection designed to engage with a recess provided on the shank when positioned vertically to secure the sleeve on the shank, and flexible members connected to the trigger.
8. The floating sinker claimed in claim 7 in which the shank is formed with an enlarged end provided with a roller designed to engage one of the flexible members, and a plurality of guides on the shank to engage the said members.
9. The floating sinker claimed in claim 7 in which the disk is partly engaged by a segmental metal cover.
10. The floating sinker claimed in claim 7 in which the shank is provided with an adjustable collar against which the sleeve is designed to bear.
11. The floating sinker claimed in claim 7, in which the shank is formed with a sleeve on the offset thereof, apertured lugs on the disc, a pin designed to engage the lugs and the sleeve, and means to vary the angular position of the pivot of the disc.

In witness whereof I have hereunto set my hand in the presence of two witnesses.

JOHN WILLIAM BOND.

Witnesses:

FRED DODSWORTH,
JACK JOHNSTON.
